Primary Examiner — Paula Greene(74) *Attorney, Agent, or Firm* — Pai Patent & Trademark Law Firm; Chao-Chang David Pai(57) **CLAIM**

The ornamental design for a data storage device, as shown and described.

DESCRIPTION

FIG. 1 is a right side perspective view of a data storage device, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

Wherein the broken lines showing various portions of the data storage device are included for illustrative purposes only and form no part of the claimed design.
